UNITED STATES PATENT OFFICE.

HAROLD E. WHITE, OF SCHENECTADY, NEW YORK, ASSIGNOR TO GENERAL ELECTRIC COMPANY, A CORPORATION OF NEW YORK.

CONTROLLING-SWITCH.

No. 861,289.

Specification of Letters Patent.

Patented July 28, 1907.

Application filed May 12, 1904. Serial No. 207,691.

To all whom it may concern:

Be it known that I, HAROLD E. WHITE, a citizen of the United States, residing at Schenectady, county of Schenectady, State of New York, have invented certain new and useful Improvements in Controlling-Switches, of which the following is a specification.

My invention relates to controlling switches for electric motors, and its object is to provide a controlling switch with a minimum number of contacts adapted for controlling the motor speed and reversing the direction of rotation.

It has been common practice heretofore, when it has been desired to control the speed of a motor in either direction, to provide one switch for speed control and a second switch for reversing the motor or motors. It is frequently advantageous to combine both functions in a single switch, as the control is thereby simplified.

Switches for combining both functions have been constructed heretofore by making the speed controlling switch rotatable in either direction from the off position and employing two sets of movable contacts, one on each side of the off position; each set being the equivalent of the contacts ordinarily employed on the speed controlling switch not having the reversing function. Such a switch simplifies the control by enabling the operator to start and control the motor in either direction, according to the direction of movement of a single control-switch; but it results in a large and costly switch, since with this arrangement the number of contacts of the ordinary controlling switch, without the reversing function, must be practically doubled, only one half the total number of movable rheostat contacts being utilized for operation in either direction.

By my invention I so arrange and organize a controlling switch that without increasing the number of contacts by more than one or two I render it possible to obtain starting and speed control in either direction, according to the movement of the switch. I accomplish this by providing two or more sets of stationary contacts disposed 180 degrees apart for two sets and a smaller angle for a greater number of sets, each set being arranged to be engaged by the movable contacts when the controlling switch is moved in either direction. In this manner I utilize all or nearly all of both stationary and movable contacts for both directions of rotation, and thereby obtain the reversing function without increase of the controller contacts.

My invention will best be understood by reference to the accompanying drawing, in which I have shown diagrammatically a controlling switch arranged in accordance with my invention and adapted to the control of a single series motor. It will be understood, however, that my invention is not limited to this par-

ticular application, but may be used to advantage on any controlling switch by means of which it is desired to obtain both reversal and speed control.

In the drawing, A represents the armature, and F the field of a series motor, which is connected through the controlling switch C to the line terminals T T'.

R is a resistance adapted for insertion in the motor circuit for the purpose of obtaining variable speed.

I have shown the contacts of controlling switch C developed on a plane surface.

It will be understood that the physical construction and arrangement of this switch may be of any well known form of rotary switch, as for instance the ordinary rotary drum type of controller. The movable contacts consist of three groups. The first group comprises twenty-one contacts electrically connected, which are indicated by the reference characters c to c^0 . The second group consists of two contacts, c^1 and c^2 . The third group consists of two contacts c^3 and c^4 .

I have shown twenty-eight stationary contacts arranged in two groups of fourteen each, these groups being displaced from each other by 180 degrees or, in other words, diametrically opposite with reference to the rotary member which carries the movable contacts. I have applied reference characters to the stationary contacts indicating their electrical connections. Thus, stationary contacts t and t^2 are connected to line terminal T. Contact t' is connected to line terminal T'. Contacts a and a' are connected to one terminal of armature A. Contacts a^2 and a^3 are connected to the other armature terminal. Contact f is connected to one field terminal. Contacts r^1 to r^9 are connected to points on the variable resistance R.

The operation is as follows: If the movable contacts of controlling switch C are moved to the left by the rotation of the controller drum to bring the stationary contacts into engagement with the movable contacts on position 1, as indicated by the dotted lines, 1, 1, a circuit will be closed as follows: from line terminal T to contact t , contact c , contact c^1 , contact r^1 , resistance R, field F, contact f , contact c^3 , contact c^4 , contact a^3 , armature A, contact a , contact c^1 , contact c^2 , contact t' , line terminal T'. The motor is consequently connected to the line with the total resistance R in series. Now if the switch is moved to position 2, as indicated by the dotted lines, stationary contact r^2 is engaged by movable contact c^2 and one section of resistance R is cut out of circuit. In position 3, stationary contact r^3 is engaged by movable contact c^3 , and the second section of resistance R is cut out of circuit. As the movable contacts are moved still further to the left, contacts c^4 , c^5 , etc., are serially and alternately engaged by the two sets of stationary contacts and further

sections of resistance R are cut out, until, at position 20, line terminal T is connected directly to the left-hand terminal field F, all of resistance R being out of circuit. Twenty speeds in one direction are thus obtained by the movement of contacts of controller C toward the left. Now, if controller C is turned to its off position, as shown, and the movable contacts are then moved to the right to position 20 by the rotation of the controller drum, a circuit is closed as follows: line terminal T, t², c, c²⁰, r¹, resistance R, field F, f, c²², c²¹, a¹, armature A, a², c²⁴, c²³, t¹, line terminal T'. The motor is thus again connected to the line with resistance R of any circuit, but with the connections of armature A reversed. The motor consequently will start in the opposite direction. As the motion of the movable contacts toward the right is continued to position 19, movable contact c¹⁹ is brought into engagement with stationary contact r², and one section of resistance R is cut out of circuit. This is continued in the several positions 20 until when position 1 is reached the motor is again connected directly to line.

Thus it will be seen that by means of my invention I am enabled to produce a switch having only twenty-five movable contacts and adapted to give twenty 25 different motor speeds in either direction.

As has been said heretofore, my invention is not limited to the control of a single motor, nor to simple rheostatic control, but is applicable to any well known type of controller in which it is desired to include the reversing 30 function. Furthermore, as has been said heretofore, more than two sets of contacts may be employed, as for instance these sets displaced by 120 degrees or four sets displaced by 90 degrees. Any of these arrangements makes it possible to use all the contacts for both directions of movement of the switch. Also while it is desirable that the angle between the sets should be 180 or 120 degrees, as the case may be, in order to secure a symmetrical arrangement of the movable contacts, it is of course possible to depart from the symmetrical location of the sets by a distortion of the movable contacts. I accordingly aim in the appended claims to cover all such modifications which are within the spirit and scope of my invention.

What I claim as new and desire to secure by Letters 45 Patent of the United States, is:

1. In combination, an electric motor, a resistance adapted to be connected in circuit with said motor, a rotary controlling switch adapted to be moved in either direction from its off position and having two sets of contacts displaced by substantially 180 degrees, a portion of the contacts of each set being connected to said motor and a portion to said resistance, and contacts movable relatively to said sets, a portion of said contacts being arranged to be engaged serially and alternately by the portions of said 50 two sets connected to said resistance when said switch is moved in either direction from its off position.
2. In combination with a resistance, a rotary controlling switch adapted to be moved in either direction from its off position and having two sets of contacts displaced by substantially 180 degrees, the contacts of each set being connected to alternate points on said resistance, and contacts movable relatively to said two sets and arranged to be engaged serially and alternately by said two sets when said switch is moved in either direction from its off 60 position.
3. In combination with a resistance, a rotary controlling switch adapted to be moved in either direction from its off position and having stationary contacts connected to points on said resistance, and movable contacts arranged 65

to engage successively all of said stationary contacts connected to said resistance when said switch is moved in either direction from its off position.

4. In combination, an electric motor, a resistance adapted to be connected in circuit with said motor, a rotary controlling switch adapted to be moved in either direction from its off position and thereby to start said motor in either direction, and having stationary and movable contacts adapted to connect various portions of said resistance in circuit with said motor, said contacts comprising two sets of stationary contacts and movable contacts arranged to engage both of said sets when said switch is moved in either direction from its off position.

5. In a rotary controlling switch adapted to be moved in either direction from its off position, two sets of substantially diametrically opposite contacts, and contacts relatively movable thereto and adapted to be engaged serially and alternately by said two sets when said switch is moved in either direction from its off position.

6. In a rotary controlling switch, a series of contacts divided into two groups displaced by an angle of substantially 180 degrees, a second series of contacts divided into two sets symmetrically disposed with respect to either one of said groups but at different angular distances from said groups, and means for rotating the contacts of one series relatively to and past the contacts of the other series.

7. In a rotary controlling switch, a series of contacts divided into two groups displaced at an angle of substantially 180 degrees, a second series divided into two groups arranged spirally about the axis of rotation of the switch, the spirals being disposed symmetrically with respect to either one of the groups of the first series but at different angular distances from said groups, and means for rotating the contacts of one series relatively to and past the contacts of the other series.

8. In a rotary controlling switch, a cylinder, two sets of contacts arranged in the form of helices symmetrically disposed on said cylinder with a greater angular distance between the ends thereof at one side of the cylinder than at the opposite side, two sets of contacts displaced at an angle of substantially 180 degrees and arranged in operative relation to the first sets of contacts, and means for producing a relative movement between the contacts on the cylinder and the remaining contacts.

9. In a rotary controlling switch, a revolvable cylinder, two sets of contacts arranged in the form of helices symmetrically disposed on said cylinder with a greater angular distance between the ends thereof at one side of the cylinder than at the opposite side, two rows of contact fingers constructed and arranged to engage the contacts on the cylinder at diametrically opposite points, and means for rotating the cylinder.

10. In a rotary controlling switch, two similar sets of revolvable contacts and two similar sets of fixed contacts constructed and arranged so that each set of revolvable contacts engages with one set of fixed contacts when the switch is rotated through a definite angle in one direction from its "off" position and with the other set of fixed contacts when the switch is rotated through a different angle in the other direction, and means for rotating said switch, the arrangement being such that circuit changes are effected at only one set of fixed contacts at a time.

11. In combination with resistances, a rotary controlling switch comprising two sets of revolvable contacts and two sets of fixed contacts constructed and arranged so that each set of revolvable contacts engages with one set of fixed contacts when the switch is rotated through a definite angle in one direction from its "off" position and with the other set of fixed contacts when the switch is rotated through a different angle in the other direction, electrical connections between the fixed contacts and the resistances, and means for rotating said switch.

12. In a rotary controlling switch, a series of contacts divided into two groups which are placed at an angle of substantially 180 degrees, a second series divided into two groups arranged spirally about the axis of rotation of the switch, the spirals being disposed symmetrically with respect to each of the groups of the first series but at different angular distances from said groups, and means for rotating the contacts of one series relatively to and

past the contacts of the other series, the arrangement being such that circuit changes are produced alternately by the contacts first on one side of the axis and then on the other.

5 13. In a rotary controlling and reversing switch, a series of contacts divided into two groups displaced by an angle of substantially 180 degrees, a second series of contacts located in a cylindrical plane and divided into two sets so arranged with reference to the two first mentioned

10 groups of contacts that a movement of one series relatively

to the other series in either direction results in bringing contacts together first on one side of the cylinder and then on the other.

In witness whereof I have hereunto set my hand this 11th day of May, 1904.

HAROLD E. WHITE.
